UNITED STATES PATENT OFFICE.

CHRISTIAN E. STENERSEN, OF CHARLOTTE, NORTH CAROLINA.

FOLDING TRAY OR LAP-BOARD.

No. 801,749.

Specification of Letters Patent.

Patented Oct. 10, 1905.

Application filed January 28, 1905. Serial No. 243,144.

To all whom it may concern:

Be it known that I, CHRISTIAN E. STENERSEN, a citizen of the United States, residing at Charlotte, in the county of Mecklenburg and State 5 of North Carolina, have invented new and useful Improvements in Folding Trays or Lap-Boards, of which the following is a specification.

This invention relates to folding trays or lap-10 boards, and has for its objects to produce a comparatively simple inexpensive device of this character which may be readily extended for use or folded into neat compact form for transportation or storage and one wherein the 15 flexible covering will when the device is extended be maintained taut and rigid to present a smooth supporting-surface for articles resting upon the board and the bracing elements maintained in secure engagement with 20 the side bars.

To these ends the invention comprises the novel features of construction and combination of parts more fully hereinafter described.

In the accompanying drawings, Figure 1 is 25 a reverse plan view of a device embodying the invention. Fig. 2 is a side view showing the same folded.

Referring to the drawings, it will be seen that the improved device comprises as a whole 30 a collapsible frame 1 and a flexible sheet or covering 2, designed to be maintained in taut distended position by the frame 1, thus to present a comparatively rigid surface or table.

The frame 1 includes in its organization longitudinal side members or bars 3, an intermediate longitudinal member or bar 4, and obliquely-disposed foldable members or links 5, herein termed the "bracing elements" and designed for maintaining the table in extended 40 condition. These elements or links 5 are preferably arranged in pairs, having their inner ends pivoted or hinged, as at 6, to the intermediate bar 4 at a point adjacent the longitudinal center of the latter and their outer ends 45 sharpened or beveled, as at 7, for engagement with corresponding recesses or seats 8, formed in the inner side edges of the bars 3, thus to maintain the frame in unfolded position and the flexible cover 2 in distended position.

50 The flexible sheet or covering 2 is by preference composed of felt and attached to the

frame by means of stitches or other attaching devices 9, threaded through perforations 10, formed at appropriately-spaced intervals throughout the length of the bars 3 and 4, 55 which latter are connected adjacent their ends by means of flexible elements or tapes 11, designed to limit the outward movement of the side bars 3 and insure proper engagement of the ends of the braces 5 therewith. 60

In practice the frame may be folded or expanded, as illustrated in Fig. 1, thus to maintain the covering in distended position, under which conditions the bracing elements or links 5 will extend obliquely of the board 65 with their beveled ends 7 seated in the recesses 8, as before explained, it being understood that in order to collapse the frame for folding the board the links will be disengaged from the seats 8, whereupon said links and 70 the bars 3 may be folded to lie upon opposite sides of the bar 4, as seen in Fig. 2, it being understood that the loose portions of the cover may then be wrapped around the frame. It is to be observed that each of the side bars 3 75 is connected at points adjacent its ends with the intermediate bar 4 through the medium of the tapes 11 and that independently-movable braces 5 are provided for maintaining each of the side bars in open condition, whereby the board presents, in effect, two separate sections, either of which may be collapsed or unfolded independently of the other to thus vary the width of the board as a whole. It 80 will also be observed that when the frame is 85 distended the tapes or ribbons 11 serve to limit the outward movement of the side bars 3 and insure proper engagement of the ends of the braces therewith, while the braces will, owing to their oblique disposition, have a 90 greater stretching or tensioning action.

The device as above described is especially adapted for use as a collapsible card-table to be readily and conveniently carried by passengers for use upon railway-trains or the like 95 and is also designed for use as a lap-board in connection with sewing or like occupations.

Having thus described the invention, what I claim is—

In a device of the class described, a collapsible frame comprising longitudinal side bars recessed adjacent their ends to provide seats,

an intermediate longitudinal bar, obliquely-disposed foldable braces pivoted to the intermediate bar adjacent the longitudinal center of the latter, said braces having their free 5 ends beveled for engagement with the said seats, and flexible tapes extended transversely of the frame and attached to the intermediate bar, and side bars for limiting the outward

movement of the latter, and a flexible cover applied to the frame.

In testimony whereof I affix my signature in presence of two witnesses.

CHRISTIAN E. STENERSEN.
